UNITED STATES PATENT OFFICE.

JOHN DESMOND, OF JACKSON, MICHIGAN, ASSIGNOR OF ONE-HALF TO
URIAH MORTON WHITE, OF TOLEDO, OHIO.

STEAM-INJECTOR.

SPECIFICATION forming part of Letters Patent No. 303,366, dated August 12, 1884.

Application filed December 4, 1883. (Model.)

To all whom it may concern:

Be it known that I, JOHN DESMOND, a citizen of the United States of America, residing at Jackson, in the county of Jackson and State 5 of Michigan, have invented certain new and useful Improvements in Steam-Injectors, of which the following is a specification, reference being had therein to the accompanying drawings.

10 My invention relates to an improvement in steam-injectors; and it consists in the chamber A, cylindric valve-chamber B, steam-conduit C, chamber-tube a, nozzle b, steam-valve D, steam-pipe E, having pipe-coupling E', connecting tube B', water-supply pipe F, pipe G, having pipe-coupling G', valve G'', elbow-joint pipe H, injecting-valve K, compound lever K', and in the combination and arrangement of the parts, substantially as hereinafter 15 more fully shown and described.

In the drawings, Figure 1 is a perspective. Fig. 2 is an elevation in section, and Figs. 3 and 4 are detail views.

In the construction of my steam-injector I 20 cast integral with chamber A the steam-conduit C, opening into the front part of chamber A at C', and into the chamber B at C'', thus connecting the front part of chamber A with the steam-valve D, and also cast integral 25 with chamber A the steam-valve chamber D, having steam-pipe E secured thereto by means of pipe-coupling E'. Chamber A has also cast integral therewith or rigidly secured therein tube a in wall a', and nozzle b, opening at one 30 end into valve-chamber B, and from thence curved and projected to nearly connect with the nozzle b' of the connecting-tube B'. The water-supply pipe F, opening into chamber A, is connected therewith by means of pipe-coupling F' and the outflow-pipe G by means of pipe-coupling G', the latter pipe being provided with 35 the outlet-valve G'', which is closed during the process of injecting water into the boiler. The cylindric steam-valve chamber B is closed 40 on one side by the screw-cap D', having recess F'', (see Fig. 4,) which recess furnishes in part the bearings of the valve-rod d, having shoulder d', and is closed on its opposite side by the screw-cap d'', having flange d'', and connects with steam-pipe E, having pipe-coupling E'. The steam-valve D consists of valve-rod 45

d, having cast integral therewith the circular disk e, having recess e', which disk is secured in the valve-chamber B by means of the screw-cap d'', and the valve is adjustable in connection with the orifice C'', leading into chamber B, and the orifice C', opening into nozzle b. The connecting-tube B' is provided with the flange g, and it, together with pipe-coupling g', Fig. 1, forms a tight joint-connection with the elbow-pipe joint H, thus preventing the possible ingress of atmospheric air. To the elbow-pipe joint H is secured the valve K, which is opened and closed simultaneously with the steam-valve D by means of 55 the compound lever K', thus admitting outflow of water into the boiler from chamber A at the moment of applying the steam.

The operation is as follows: The valve D is first adjusted by compound lever K' to bring 60 recess e' of circular disk e in line with the orifice C' of the steam-conduit C, whereupon water is elevated by action of the steam from supply-pipe F, and carried forward by it as it proceeds from section-chamber M 65 through tube a into a section, M', and thereupon by moving the compound lever K' the recess e is brought into line with the nozzle b. The steam proceeding from the nozzle forces the water out through connecting-tube B' and through valve K into the boiler, the valve being opened simultaneously with the alignment of recess e' with nozzle b by movement of the compound lever K', which is so arranged in connection with these valves as to 70 perform both these operations together by one and the same movement thereof. When a sufficient quantity of water has been injected into the boiler, the outlet-valve G'' is opened, and the surplus water contained in section M' is 75 thus permitted to flow therefrom through pipe G, thus preventing precipitation of water-sediment in said section, and its ultimate injection into the boiler with water as supplied thereto.

Having described my invention, what I 80 claim is—

1. A steam-injector operated by means of a compound lever for simultaneously opening and closing valves for ingress of steam and egress of water to the boiler, substantially as 85 shown and described.

2. A steam-injector, consisting of chamber A, divided into sections M M', supply and outlet water-pipes, a steam-conduit, steam and water valves, tube *a*, nozzle *b*, connecting-tube B', and a compound lever for admission of steam into chamber A and egress of water therefrom to the boiler simultaneously, substantially as described.

3. The combination of chamber A, having conduit C, tube *a*, nozzle *b*, connecting-tube

B', steam-valve D, injecting-valve K, supply-pipe F, emptying-pipe G, and compound lever K', substantially as shown, and for the purpose described.

In testimony whereof I affix my signature in presence of two witnesses.

JOHN DESMOND.
